UNITED STATES PATENT OFFICE

157,557

COMBINATION RADIO AND PHONOGRAPH CABINET

Samuel E. Adler, Chicago, Ill., assignor to Admiral
Corporation, Chicago, Ill., a corporation of
Delaware

Application July 29, 1948, Serial No. 147,840

Term of patent 14 years

(Cl. D56—4)

To all whom it may concern:

Be it known that I, Samuel E. Adler, a citizen of the United States, and resident of Chicago, in the county of Cook, State of Illinois, have invented a new, original, and ornamental Design for a Combination Radio and Phonograph Cabinet, of which the following is a specification, reference being had to the accompanying drawings, forming a part thereof.

Fig. 1 is a perspective view of a combination radio and phonograph cabinet, showing my new design; and

Fig. 2 is a different perspective view of the cabinet as it appears in open condition for access to the phonograph and radio controls.

I claim:

The ornamental design for a combination radio and phonograph cabinet, substantially as shown.
SAMUEL E. ADLER.
